UNITED STATES PATENT OFFICE.

AUD R. MARSHALL, OF YAKIMA, WASHINGTON.

SWING.

Application filed September 6, 1927. Serial No. 217,738.

This invention relates to swings, and more particularly to a swing of simple construction and portable nature, designed to afford healthful body developing exercise, as well 5 as amusement and pleasure.

An object of the invention is to provide a frame construction dispensing with the use of bolts and other fastening devices and providing a "knock-down" construction which 10 may be easily assembled and which, when assembled provides a rigidly interlocked frame. In accordance with this object, a feature of 15 the invention consists of a frame having side and cross members with uprights at their junctions, said members and uprights being interjoined by mortise and tenon. Additionally, and as a further feature, a wedging interlock is provided for a member so joined.

A further object of the invention is to provide a suspended swing which may be hung low for the use of children and which is provided with arm and feet operating means to 20 provide healthful exercise and actuating means for the swing.

25 A consideration in the manufacture and sale of all swings is their demountability, packing space and ease of assembly, since all these elements enter into the cost and marketability of such devices. It is therefore an 30 object of my invention to provide a complete demountable or "knock-down" swing, requiring a minimum of work in assembly and dispensing, to a large extent, with the use of nuts and bolts which are often lost in transit 35 and are often hard to replace in the particular size used.

The described and other features and advantages will be more fully apparent from the following detailed description when read 40 in connection with the accompanying drawings forming part thereof and in which:

Figure 1 is a perspective view of the assembled swing,

45 Figure 2 is a longitudinal section on the line 2--2 of Figure 1,

Figure 3 is a bottom plan view of the frame and corner uprights, only, assembled,

50 Figure 4 is a detail of the mortise and tenon joint and interlocking wedge means of the frame members and uprights,

Figure 5 is a top plan view of the swing carriage proper, detached,

55 Figure 6 is a detailed view of the rear swing actuating crank hanger.

Referring to the drawings by numerals, 1 indicates the side members of a rectangu-

lar frame, and 2, the cross members of this frame or base of the swing. From the junction of the side and cross member of the swing, uprights 3 are provided, from the upper ends of which the swing proper is suspended by means of hangers journaled at their upper ends as will be later described. 60

The side and cross members of the base frame of the swing and the uprights at their junction are interjoined into a rigid frame without the use of securing devices such as screws or bolts as follows: The lower ends of the uprights are provided with vertical slots 4 therein substantially centrally thereof and 65 have one edge formed with a wedging bevel 5. The slots 4 of the uprights embrace short ribs 7, acting as tenons 7 and mortises 4, the ribs 7 being formed by mortising or channelling the opposite sides of cross bars 2 70 forming mortises with which the lower ends of the uprights 3 at opposite sides of the slots 4 engage. The cross bars and uprights when thus joined are seated on and locked to the side bars 1 by means of the following structural features. The side bars, adjacent to 75 their ends are channelled on their inside faces as at 9 and are mortised at 8 on their outside edges to receive the tenons formed by the ribs 7 of the cross bars, these ribs being of a 80 width equal to the thickness of uprights 3 and the channelled portions of the side frames. The channel 9 acts also as a mortise to receive the lower end of the uprights 3, one side of the channels being formed with 85 bevelled or wedging edges 10, which cooperate with the wedges 5 of the uprights as the cross bars are forced down and seated on the side bars to cause the uprights and cross bars 90 wedgingly to interlock with the side bars. 95

The cross bars 2 are locked by the mortise and tenons 7-8 against loosening movement lengthwise of the frame, and are rigidly held crosswise by the shoulders of the mortise 6 engaging opposite sides of the side bars. 100 The uprights 3 are maintained in vertical position by the firm engagement of the lower slotted ends with the sides of the mortise 6 of the cross bar and by the wedging interlock of its end edges with the sides of the 105 mortise or channel 9 of the side bar 1. The described construction, while a "knock-down" provides for a rigid construction when assembled and interlocked as described.

The upper ends of the uprights 3 are provided with vertical notches 7 therein to receive the rock arms 12 formed by offsets at the 110

upper ends of the hanger for the swing itself. These hangers are, preferably, in the form of strong metal rods, the upper ends of which are laterally offset as at 12 as described and 5 provided with enlarged heads 13 to retain them in the slots 11. The hanger for the forward end of the swing is in the form, substantially of a U shaped bar 4 while the hanger 15 for the rear end of the swing while 10 of a generally U-shape is provided with a central crank portion 16 bent upwardly from its lower end so that the portion 17 between the crank 16 and the side bars of the hanger 15 constitute rock shafts or arms.

15 These hangers support a swing construction as follows: Runner bars 18 extending longitudinally of the base frame and arranged in parallel, have notches 19 formed at aligned points on their lower edges in which 20 the cross bar 20 of the front hanger 14 journals to support the runners and in which the rock arms 17 of the rear hangers 15 likewise seat and journal. Intermediate the ends of the runners 18, there are formed upward extensions 21 forming a seat base. The upper edge of this base is provided with a plurality of uniformly spaced sockets 22 into which seat studs 23 projecting from the base of a bucket seat 24, adjustably to position this seat 25 longitudinally on the base 21. Pivoted at 25 on the inner sides of the seat base 21 are hand levers 26 connected by head and nut at opposite ends of a cross rod 27 which may be said 30 to form a handle bar, and having pivotally mounted thereon, adjacent to their lower ends, connecting bars 28, the rear ends of which are split, as seen in Figures 1 and 2 at 35 29, and bored to provide bearings for the crank 16 of the hanger 15, bolts 30 retaining 40 the cranks 16 in its bearings after the same has been inserted through the split end 29. The lower ends of the handle bar levers 26 extend through slots 31 (Fig. 2) appropriately located in a foot board 32 which is hung 45 from the seat base 21 and corners 18 by appropriate stirrups 33, the lower end of the handle bar levers thereby connecting this foot board with the levers so that foot pressure applied through the suspended foot board 32 50 will cooperate with these levers and the crank bars 28 to oscillate the crank 16 and rock arm 17 and cause the swing to move to and fro. The stirrups 33 are inserted from the bottom of the foot board through appropriate 55 apertures and are retained therein by bends at their lower ends, correspondingly bent portions at their upper ends being inserted through and extending preferably beyond the bores 34 in the seat base. The only bolts that 60 are used in the entire assembly are those connecting the forward and rear ends of the crank arms 28, the bolts 25 pivoting the handle bar levers 26 and the bolt of the handle bar 27.

65 In connection with the swing assembly de-

scribed, it is to be noted that I have inclined the pairs of front and rear uprights 3 toward each other and upwardly from their base. This, as will be seen from Figure 2 of the drawings, is for the purpose of positioning the side bars of the hangers perpendicular to the frame support or base with the swing section centered therein. The hangers for the swing section also act through their side bar and crank arms to cross brace the runners 18, 75 these being additionally cross braced by the spanning seat 24 superimposed on the upward extensions 21 of the runners.

70 The described construction provides a low hung swing, especially suitable for children, so both for amusement purposes and as an exercising device to develop their bodies. It will be noted that the construction is such that both arms and legs are conjointly exercised in operating the swing since the levers 26 are 80 pushed forwardly and the foot board is pushed upwardly and backwardly by the seat occupant for actuation of the swing forwardly and the levers are pulled backwardly and the foot board downwardly and forwardly 85 in the reverse movement of the swing, thereby naturally bracing the feet and back for the pull or thrust of the arms and giving complete muscular exercise. It will be obvious that the seat 24 can be easily adjusted 90 on its base to fit the child to the swing for operating purposes, and that the thrust on the levers 26 or connecting handle bar 27 95 aided by foot pressure against the foot board or pedal 32 is effective to cause the swing to 100 oscillate to and fro with its hangers in their supporting frame. It will also be evident that the described construction may be disassembled and packed piece-meal for shipment. This is true as to every portion of the assembly, so that the minimum in the way of space 105 is required for packing. The simplicity of the construction and the minimum of bolts required makes its assembly a comparatively 110 easy matter.

Having described my invention, what I claim and desire to secure by Letters Patent is:

110 1. In a swing, a stationary supporting frame having pairs of spaced uprights at opposite ends, a swing section including runners and a seat mounted thereon, U-shaped hangers having their upper ends journaled in said uprights and their lower cross bar underlying and supporting said runners at opposite ends, 115 one of said hangers having a crank portion between the runners, and hand and foot operable means having common operating connections to said crank.

120 2. In a swing, a stationary supporting frame having pairs of spaced uprights at its opposite ends, a swing section including runners and a seat mounted thereon, U-shaped hangers journaled in said uprights at their upper 125 ends and underlying and supporting said run-

ners at opposite ends, one of said hangers having a crank portion between the runners, a hand lever pivoted on a seat runner and having operating connection with said hanger crank effective to move said hangers and swing section in the reverse direction of lever motion, a foot pedal, and operative connection between said foot pedal and hand lever.

3. In a swing, a frame, U-shaped hangers journalled therein at their upper ends, runners mounting a seat and grooves on their under faces to receive and journal the bottom cross bars of said hangers for oscillation therewith, one of said hangers having a crank portion between said runners, a hand lever on said runners, a connecting bar between said lever and said hanger crank, and a foot board suspended from said runners for swinging movement and having slotted connection with said hand lever.

4. A swing having a supporting frame, runners, a seat superimposed thereon, U-shaped hangers journalled at their upper ends on the frame and depending therefrom to underlie and support the runners and seat from the frame for swinging movement, one of said hangers having a crank portion between the runners, a hand lever operatively connected to said hanger crank, a foot member having operative connection with said lever, said parts having connections providing for complete disassembly of the several parts thereof.

5. In a swing, a supporting frame comprising side and cross base members with corner uprights, parallel runners, a seat superposed on and spanning said runners, U-shaped hang-

ers having their upper ends journalled in said uprights and having their bottom cross members underlying and journalled on said runners, one of said hangers having a crank portion between the runners, an operating lever connecting a runner and said crank, a foot pedal connected to said lever, and means interconnecting said parts constructed and arranged to permit complete disassembly thereof for packing.

6. In a swing, a frame comprising longitudinal side members and end cross members having interfitting tongued and grooved overlapping edges and adjoining recessed side faces, standards upright from the four points of junction of the side and cross members having their lower ends formed to seat in the adjoining recessed face portions of said members wedgingly to interlock therewith, substantially U-shaped hangers pivotally mounted at their upper ends on and depending from the pairs of standards at each end of the frame, seat-spanned runners extending in parallel longitudinally of the frame having alined grooves in their under faces to receive and journal the bottom cross bars of the hangers, one of said cross bars having a crank formed thereon between the runners, an operating lever pivotally mounted on a runner and operatively connected with said hanger crank to oscillate said crank and the runners mounted thereon, and a foot pedal board pivotally hung from said runners and operatively connected with said operating lever conjointly to actuate said hanger crank therewith.
